UNITED STATES PATENT OFFICE.

NATHANIEL LOMBARD, OF WORCESTER, MASSACHUSETTS, ASSIGNOR TO HOLYOKE MACHINE COMPANY, OF WORCESTER, MASSACHUSETTS, A CORPORATION OF MASSACHUSETTS.

SPEED-CONTROLLING MECHANISM.

1,305,386.

Specification of Letters Patent.

Patented June 3, 1919.

Application filed September 20, 1915. Serial No. 51,673.

To all whom it may concern:

Be it known that I, NATHANIEL LOMBARD, a citizen of the United States, residing at Worcester, in the county of Worcester and 5 Commonwealth of Massachusetts, have invented a new and useful Improvement in Speed-Controlling Mechanism, of which the following, together with the accompanying drawings, is a specification.

10 The present invention relates to a speed controlling mechanism, and is particularly concerned with the provision of a mechanism of this class which is adapted to limit the speed of large water wheels, such as those 15 employed to operate the grinders in pulp mills.

The equipment of such wheels and other 20 similar prime movers with governing mechanism, adapted to maintain them at a constant speed, under varying conditions of load and water pressure, involves a large 25 expense and the provision of complicated and sensitive devices, acting on the gate which controls the water supply, to render 30 said gate delicately and instantly responsive to variations in the speed of the wheel. Since the prime consideration under the 35 special circumstances outlined above, is the avoidance of excessive speeds which might cause bursting of the grinder, a speed 40 controlling mechanism which prohibits the attainment of such excessive speeds, without reference to the automatic return of the wheel to so-called normal speed, and with- 45 out reference to an automatic increase in speed when the same falls below normal, has been found most economical and efficient for the purposes described. The present invention aims to provide a mechanism having the 50 above described principle of operation, and effecting a positive reduction in the speed of the wheel when said speed exceeds a predetermined maximum; the gate being subject thereafter to manual control, to attain 55 any speed desired below said predetermined maximum. The mechanism by which this result is accomplished is fully set forth in the following description and illustrated in the accompanying drawings, in which—

50 Figure 1 is a perspective view of the apparatus embodied in my invention.

Fig. 2 is a vertical sectional view of a portion of said apparatus.

Fig. 3 is a detail sectional view on line 3—3, Fig. 2.

Similar reference characters refer to similar parts in the different figures.

Referring first to Fig. 2, there is shown a housing 1, which supports and incloses a centrifugal governor 2 of ordinary construction. The governor shaft 3, which is hollow, for the passage of a reciprocating governor rod 4, is rotated by gearing 5 from a shaft 6, driven directly by a pulley 7, having a belt connection with a shaft 49. The latter is geared, as at 50, to a shaft 32 which is driven constantly from the shaft 51 of water wheel 52 by a pulley 36 and belt connection 53. The weighted members 8, 8 of the governor act in the well known manner upon the rod 4, which is maintained by the springs 9, 9, approximately in the position shown in Fig. 2, under normal operating conditions of the water wheel. When the speed of said wheel exceeds a predetermined maximum, 75 the outward movement of members 8, 8 serves to depress rod 4, causing the latter to inaugurate the action of the gate controlling devices in the manner about to be described.

The housing 1 also supports a single-acting piston cylinder 10, having a pipe connection 11 with a valve casing 12 disposed interiorly of said housing. The valve casing 12 provides a chamber 13 in direct communication with the cylinder 10 through pipe 85 connection 11, and also normally in communication with the atmosphere through a gravity check valve 14. The latter is held open, as shown in Fig. 2, by the support afforded its valve stem 15 by a tongue 16 on the free end of a lever 17, pivoted to the casing, and enlarged intermediate its ends, as shown at 18, Fig. 3, to provide for the pivotal connection thereto of the rod 4, which normally supports said lever in the 90 position shown. The casing 12 provides a second chamber 19, in constant communication through a pipe connection 20 with a pressure tank 21, Fig. 1, in which a supply of compressed air, or other pressure medium, 100 is maintained, in any well known manner, as by a pump 22. A valve 23, normally

held closed by a spring 24, controls the flow of pressure fluid from the chamber 19 to the chamber 13; the stem 25 of valve 23 extends into the path of the tongue 16 of lever 17, being spaced slightly therefrom, as shown in Fig. 2, when the rod 4 is in normal position.

The cylinder 10 contains a piston 26 having a rod 27 projecting through the casing 1, and secured to a sleeve 28, which is pivoted, as shown at 29, in the forked end of a vertical lever 30, pivoted at 31. The lever 30, intermediate its ends, provides a journal bearing for one end of the horizontal shaft 32, the other end of which is journaled in a bearing 33, capable of swinging about the vertical axis of its trunnions 34 in a bracket 35 receiving said trunnions. The shaft 32 is constantly rotated in any well known manner, as by the belt connection 53, from the water wheel shaft 51 with the pulley 36 on said shaft. The shaft 32 has keyed thereto a friction wheel 37, and in the position of the piston 26, shown in Fig. 2, a spring 38, acting through the piston rod 27 on the lever 30, yieldingly maintains the shaft 32 in the direction of the housing 1, Fig. 1, so that the periphery of rotating wheel 37 is slightly spaced from the periphery of a friction wheel 39, on a shaft 40. The shaft 40 is manually rotatable to vary the gate opening of the water wheel, the same, in the present instance, being indicated as a rotary valve device within a casing 54, which is operable to control communication between a supply conduit 55 and the pipe 56 leading to the water wheel.

The sleeve 28 provides an extension 41, passing loosely through the free end of a lever 42 which is pivoted at 43 and is disposed substantially parallel to the lever 30. The projecting end of extension 41 has pivoted thereto, by means of a pin 44, a locking member 45, which, in the position shown in Fig. 1, forces the lever 42 toward the housing 1, and holds a shoe 46, carried by said lever, against the periphery of wheel 39 to prevent rotation of said wheel. When the member 45 is rotated, on the pin 44 through ninety degrees, to bring its normally horizontal side in contact with the face of lever 42, the latter is enabled to rock outwardly, under the pressure exerted by a spring 47, confined on the extension 41 between lever 42 and a collar 48. The pressure of shoe 46 is thereby taken off the wheel 39, enabling the shaft 40 to be manually rotated, to open or close the gate of the water wheel.

The operation of the speed controlling mechanism is as follows:—Under all conditions, except when the speed of the water wheel goes above a predetermined maximum, the governing mechanism is inoperative and maintains the relation of parts shown and described with reference to Figs. 1 and 2,

the spring 38 acting to draw the extension 41 inward toward the housing 1, and thereby holding the shoe 46 against the wheel 39, to prevent movement of the shaft 40 and the gate. If it is desired to change the gate opening, the locking member 45 is rocked, releasing the wheel 39 from the shoe, and permitting the manual rotation of shaft 40, after which the member 45 is returned to the position shown in Fig. 1, to hold the wheel 75 and shaft stationary. The mechanism is adjusted so that the attainment of a predetermined maximum speed by the wheel will cause the weighted members 8, 8 to diverge enough to depress the rod 4 and thereby 80 carry tongue 16 against the valve stem 25, opening valve 23 against the pressure of spring 24 and allowing the gravity valve 14 to close. The pressure prevailing in chamber 19 is thereby made effective against piston 26, moving the rod 27 and extension 41 outwardly, against the yielding pressure of spring 38. The levers 30 and 42 are thereby rocked simultaneously about their pivots, the rocking of lever 42 carrying shoe 46 90 away from the wheel 39, and the rocking of lever 30 carrying the constantly rotating wheel 37 into contact with wheel 39, to cause the rotation of the latter and the shaft 40 in a direction to effect the closing movement 95 of the gate. As the supply of water to the wheel is thus decreased, the speed of the wheel becomes lower and lower, until the members 8, 8 are no longer able to maintain the rod 4 depressed. The upward movement 100 of said rod by the springs 9, 9 permits the valve 23 to close, and opens the valve 14, thereby releasing the pressure on piston 26, and allowing the spring 38 to return the levers 30 and 42 to normal position. This 105 action of spring 38 causes the movement of wheel 37 away from frictional contact with wheel 39, stopping the closing movement of the gate, and also causes the shoe 46 to move against wheel 39, holding the gate in 110 the partly closed position to which it has been moved.

I claim,

1. In apparatus of the character described, the combination with a gate controlling member of a water wheel, of an actuating means therefor normally held out of operative position, and means responsive to an increase only in the speed of said wheel for moving said actuating means into operative position whereby the position assumed by said gate controlling member in response to its actuation is unchanged by the ensuing reduction in speed of said wheel.

2. In apparatus of the character described, the combination with a gate controlling member of a water wheel, of means for retaining said gate controlling member in a predetermined position, an actuating means for said gate controlling member

normally held out of operative position, and means responsive to an increase in the speed of said wheel for simultaneously releasing said retaining means and for moving said 5 actuating means into operative position.

3. In apparatus of the character described, the combination with a gate controlling member of a water wheel, of means for retaining said gate controlling member in a

10 predetermined position, means for releasing said retaining means to permit the manual adjustment of said gate controlling member, an actuating means for said gate controlling member normally held out of operative position, and means responsive to an increase in the speed of said wheel for simultaneously releasing said retaining means and for moving said actuating means into operative position.

20 4. In apparatus of the character described, the combination with a gate controlling member of a water wheel, an actuating means therefor normally held out of operative position, pressure actuated means for 25 moving said actuating means into operative position, and means responsive only to an increase in the speed of the wheel for rendering said pressure actuated means effective.

30 5. In apparatus of the character described, the combination with a gate controlling member of a water wheel, of means responsive to an increase in the speed of said wheel for inaugurating the gate-closing 35 movement of said member, and means for retaining said member in the position to which it is moved, after the speed of the wheel has been decreased.

6. In apparatus of the character described, the combination with a gate controlling member of a water wheel, of a con-

stantly rotating actuating means therefor normally held out of operative position, and means responsive to an increase only in the speed of said wheel for moving said actuating means into operative position to inaugurate the gate-closing movement of said member whereby the position assumed by said gate controlling member in response to its actuation is unchanged by the ensuing 50 reduction in speed of said wheel.

7. In speed controlling mechanism of the character set forth, the combination with a movable speed regulating member, of an actuating means therefor normally held out 55 of operative position, pressure actuated means for moving said actuating means into operative position, and means responsive only to an increase in the speed of the device whose speed is to be controlled, for 60 rendering said pressure actuated means effective.

8. In speed controlling mechanism of the character set forth, for regulating the supply of motive fluid to a prime mover, the combination with a movable regulating member, of an actuating means therefor normally held out of operative position, and means responsive only to an increase in the speed of said prime mover for moving said actuating means into operative position whereby the position assumed by said regulating member in response to the movement of said actuating means is unchanged by the ensuing reduction in speed of said prime 75 mover.

Dated this seventeenth day of September, 1915.
